CLAIM

The ornamental design for a toy ball, as shown and described.

DESCRIPTION

FIG. 1 is top perspective view of a toy ball, showing our new design.

FIG. 2 is a bottom perspective view thereof.

FIG. 3 is a top plan view thereof.

FIG. 4 is a bottom plan view thereof.

FIG. 5 is a right elevation view thereof.

FIG. 6 is a left elevation view thereof.

FIG. 7 is a front elevation view thereof; and,

FIG. 8 is a rear elevation view thereof.

The broken lines in the drawings depict portions of the toy ball that form no part of the claimed design.
